UNITED STATES PATENT OFFICE

126,587

DESIGN FOR A DIRECTION SIGNAL OR SIMILAR ARTICLE

Leon Lapidus and Benjamin Lapidus,
Brooklyn, N. Y.

Application August 15, 1940, Serial No. 94,435

Term of patent 3½ years

To all whom it may concern:

Be it known that Leon Lapidus and Benjamin Lapidus, citizens of the United States and residents of Brooklyn, in the county of Kings and State of New York, have invented a new, original, and ornamental Design for a Direction Signal or Similar Article, of which the following is a specification, reference being had to the accompanying drawing, forming part thereof, in which—

Fig. 1 is a front elevational view of a direction signal embodying our new design;

Fig. 2 is a top plan view thereof; and

Fig. 3 is an end elevational view thereof.

We claim:

The ornamental design for a direction signal or similar article, substantially as shown.

LEON LAPIDUS.
BENJAMIN LAPIDUS.
